UNITED STATES PATENT OFFICE.

SAMUEL B. SMITH, OF CLEVELAND, OHIO.

HOVER.

1,223,433.

Specification of Letters Patent. Patented Apr. 24, 1917.

Application filed November 27, 1916. Serial No. 133,702.

To all whom it may concern:

Be it known that I, SAMUEL B. SMITH, a citizen of the United States, residing at Cleveland, in the county of Cuyahoga and State of Ohio, have invented certain new and useful Improvements in Hovers, of which the following is a specification.

This invention relates to improvements in hovers for chicks and other fowl. 10 The object of the invention is to provide a heater of the coal burning type in connection with a canopy which will be simple in construction, effective in operation, and economical in manufacture, thereby presenting 15 a brooder or hover having a canopy attached to the stove described in my prior Patent No. 1,189,301, issued July 4th, 1916.

In the drawings:—

Figure 1 represents a top plan view of 20 a hover embodying my improvements with the canopy partly broken away.

Fig. 2 is a vertical section of the same with the canopy also partly broken away.

Fig. 3 is a vertical section of the upper 25 portion of the same showing the magazine removed and replaced by a cover.

Referring to the drawings, the stove which I employ comprises a hollow base portion 10 in which is arranged a bottom wall 11, 30 and the interior of the base above this bottom wall constitutes the ash pit indicated at 12. To the under side of the wall 11 is secured a sheet of suitable heat insulating material 13, preferably asbestos, and at the 35 under side of the said sheet is preferably arranged a metallic plate 14 which serves to reinforce the insulating sheet and hold it in position. On the base portion 10 is mounted a fire pot section 15, and above 40 the fire pot section 15 is mounted the combustion chamber section 16, the fire pot section and the combustion chamber section being bolted together in the usual manner.

In the bottom of the fire pot is mounted the 45 grate 17 provided with an arm 18 connected to a link 19 for the purpose of rocking the same. In the top of the combustion chamber section is formed an opening 21 which is adapted to receive the lower end of a magazine section 22. The magazine section is provided with a removable cover 23 at its upper end to permit of the fuel being supplied thereto. In the top of the combustion section is formed a flue opening 24, and

adjacent to the flue opening is formed a 55 check draft opening 25. The check draft opening 25 is provided with a cover 26 which has at one side small trunnions 27 which are mounted in suitable bearings on the top of the combustion section, thereby 60 permitting the cover to swing up and down on the said trunnions. The said cover 26 is provided with an arm 28 which projects outwardly from a point between the trunnions and beyond the edge of the combustion section. On the side of the stove near the base thereof is secured a rigid arm or bracket member 30 which, near its outer end, carries an enlargement or head 31. Below the rigid arm 30 is arranged a lever 70 33 which is provided with a head 34 corresponding to the head 31 on the rigid arm. The said lever 33 is fulcrumed or connected at its outer end to the outer end of the rigid arm 30 by means of a screw threaded bolt 75 35 which passes up loosely through the end of the lever and through the end of the arm 30. On the bolt 35 is arranged a wing nut 36. The opposite end of the lever 33 is connected to the arm 28 on the cover 26 by a 80 link 38. Between the heads on the rigid arm 30 and the lever 33 are arranged a pair of thermostatic elements 37 which are of the usual construction. Within the combustion chamber on the under side of the top there 85 below the flue opening and the draft opening is arranged a check draft chamber 39 which is entirely closed except at one end adjacent to the check draft opening in the top of the combustion chamber. 90

It will readily be understood that when there is fire in the stove the products of combustion in order to escape will have to enter the check draft chamber, then pass below the check draft opening and escape 95 through the flue-opening. When regulating the stove for maintaining a predetermined temperature the wing nut is so adjusted that there will be the necessary space between the heads on the rigid arm 30 and the lever 33 100 to accommodate the thermostatic element when expanded for that degree of temperature, and there will therefore be no pressure on the lever. Now, if the temperature rises beyond this predetermined degree the 105 thermostatic element will expand causing the inner end of the lever to swing down, which will draw down the link 38 connected

with the arm 28 on the check draft cover 26 causing the cover to swing up and permitting the outer air to pass into the check draft chamber thereby reducing or counter-
5 acting the draft through the flue. As the stove cools down the temperature will diminish and the thermostatic elements will contract, and when the pressure is removed from the lever 33 the check draft cover will
10 swing down of its own weight.

Surrounding the stove thus described is a canopy 40, preferably constructed of sheet metal of flaring form, a fabric curtain 41 being hung from its lower edge. The
15 canopy is provided with a central opening, about the edges of which is secured a metallic ring 42 having an inturned flange 43 which hangs on the outer edge of the combustion chamber section 16, the flange
20 being cut away slightly at the points where it encircles the magazine 22 and the flue opening 24, and the ring 41 being offset or recessed as at 44 to accommodate the link 38. By this arrangement the draft and fuel
25 openings are located outside of the canopy.

In Fig. 3 I have shown the magazine 22 removed and the opening into the section 41 closed by a removable cover 45, it being usual to supply each stove with not only the
30 removable magazine 22 but also a cover such as the one 45 to close the opening to the combustion chamber when it is not desired to employ the magazine.

Means are provided for raising the canopy
35 from the stove, consisting of a bail 46, hinged to ears on the metallic ring 42 and a rope 47 passing about pulleys 48.

Having thus described my invention, I claim:

40 1. In a stove, the combination of a base portion, a two-part combustion chamber having its greatest diameter near the center, each part thereof being frusto-conical in form, the top of the same being flat and
45 formed with draft and fuel openings eccentrically arranged, a damper in the draft openings, a thermostatic device projecting from the base portion, a vertical damper rod connected thereto, means connecting said
50 damper and said rod, and a canopy supported at the upper part of the combustion chamber and centrally apertured so that the draft and fuel openings are located outside of the canopy.

55 2. In a stove, the combination of a base portion, a two-part combustion chamber, each part being substantially frusto-conical in form, the two sections being superimposed so that the larger portions of the chamber are connected together, the flat top of the chamber being formed with draft and fuel openings, a damper in the draft opening, a thermostat arm secured to the base, a
60 movable thermostat lever mounted below the arm, means connecting the thermostat

lever with the damper, and a canopy supported at the upper part of the chamber and centrally apertured so that the draft and fuel openings are located outside of the canopy.

3. In a stove, the combination of a base portion, an upper stove section above the base having its widest part near the center of the stove and having its sides converging upwardly and downwardly from the center, the flat top of the upper stove section being formed with draft and fuel openings eccentrically arranged, a damper in the draft opening, a thermostatic device projecting from the base portion and a vertical damper rod connected thereto, means connecting said damper and said rod and a vertically-movable canopy supported on the upper part of the upper stove section and centrally apertured so that the draft and fuel openings are located outside of the canopy.

4. In a stove, the combination of a base portion, a two-part combustion chamber, each part being substantially frusto-conical in form and the chamber having its greatest diameter near the center thereof, the flat top of the same being formed with draft and fuel openings eccentrically arranged, a damper in the draft opening, a thermostatic device projecting from the base portion, a vertical damper rod connected thereto, means connecting said damper and said rod and a canopy supported at the upper part of the chamber and centrally apertured so that the draft and fuel openings are located outside of the canopy.

5. In a stove, the combination of a base portion, a combustion chamber having its greatest diameter near the center thereof, the sides of the same converging upwardly and downwardly from the center, the top of the chamber being formed with check draft and fuel openings eccentrically arranged, a damper in the draft opening, a canopy supported at the upper part of the combustion chamber and centrally apertured so that the draft and fuel openings are located outside of the canopy, a thermostatic device projecting from the base portion, a vertical damper rod extending upwardly therefrom and means connecting the damper and rod.

6. In a stove, the combination of a stove having solid unbroken walls, a reduced top portion formed with smoke-flue, fuel and check draft openings, a check draft chamber located within said top, at one side of the center thereof, and communicating with, said smoke flue and check draft openings, said draft chamber being closed to the combustion chamber of the stove except at one end, a canopy projecting from said stove, a check draft damper and a thermostat enclosed by the canopy and controlling said

damper, said canopy having a central opening fitting over the reduced stove top and encircling the draft chamber, the top of the canopy being substantially flush with the reduced top portion so that the said openings in the stove top will lie outside of the canopy, substantially as described.

In testimony whereof, I have hereunto set my hand this 25th day of November, 1916.

SAMUEL B. SMITH.
